UNITED STATES PATENT OFFICE.

WILLIAM CHARLES BAYLESS AND JAMES CUMMING NICHOLS, OF MOSSY CREEK, TENNESSEE.

WATER FILTER AND CUT-OFF.

SPECIFICATION forming part of Letters Patent No. 398,218, dated February 19, 1889.

Application filed May 12, 1888. Serial No. 273,726. (No model.)

To all whom it may concern:

Be it known that we, WILLIAM CHARLES BAYLESS and JAMES CUMMING NICHOLS, citizens of the United States, residing at Mossy Creek, in the county of Jefferson and State of Tennessee, have invented new and useful Improvements in Water Filters and Cut-Offs, of which the following is a specification.

Our invention relates to a new and improved water filter and cut-off, the purpose thereof being to strain and purify the water as it passes into the cistern or other receptacle.

It is a further purpose of our invention to provide simple and easily-operated means whereby the water may be cut off from the cistern or other reservoir and the intermediate straining and filtering devices and delivered to any point other than the said cistern, the cut-off being provided with an automatic lock or holding device, whereby it is held in normal position against any force ordinarily brought to bear thereon.

To these ends the invention consists in the several novel features of construction and new combinations of parts hereinafter fully described, and then definitely pointed out in the claims.

In the accompanying drawings, Figure 1 is a front elevation of the mechanism employed in our invention. Fig. 2 is a central vertical section of the parts shown in Fig. 1. Fig. 3 is an edge or side elevation of the parts shown in Fig. 1. Fig. 4 is a side elevation of filter made separate from cut-off, and Fig. 5 is a central vertical section of the parts shown in Fig. 5.

In the said drawings, the reference-numeral 1 designates the frame or casing of water filter or strainer, said casing being composed of two parallel walls, 2, inclosed by a front and back, 3, and forming a closed chamber, 4, having an opening, 5, at the top and a similar opening, 6, at the bottom. The top opening is designed to connect by a pipe with the roof of a building. A chute, 8, is hinged at its center within the casing by a pivot, 9, and to one end of the chute is hinged or pivoted a lever extending out through and movable length-

wise in a slot, 12, arranged in a vertical plane 50 in the top of the casing. The lever rests against and slides lengthwise upon the lower edge of the slot, and is provided at its outer end with a weight, 10, which, by pressing the lever down upon the lower edge of the slot 55 12, holds the chute 8 when in the position to divert the water through the side outlet, while the downward pressure of the weight holds the chute when tilted to divert the water upon the strainers, as shown by dotted lines, Fig. 60 1. The lever is pivoted to the chute, so that the latter is tilted by simply pushing the lever inward or pulling it outward, and as the chute tilts the pivotal connection of the lever permits the requisite swinging motion of 65 the lever on the lower edge of the slot 12, which therefore acts as a fulcrum. By moving the lever lengthwise the chute can be tilted to the position shown in full lines, Fig. 1, to divert the water to a duct, 19, and through 70 the lateral exit-orifice 14, and by moving the lever to tilt the chute to the position shown in dotted lines, Fig. 1, the water is diverted directly downward into the casing over a strainer or filter composed of a series of parallel bars, 15, which intercept the coarser matter or débris carried by the water.

The duct 19 is composed of a trough-shaped plate inclined from its upper end to the lateral exit-orifice 14 in the side of the casing 1, 80 said plate having its upper edge lying under the center pivot of the chute 8, or approximately, whereby the water may be directed to said duct without passing to the strainers, or the water can be directed down into the 85 casing and through the strainers.

Beneath the parallel bars 15 is arranged a foraminous screen, 16, having an inclination opposite to that of the parallel bars 15. The water passing through these bars leaves the 90 coarser foreign matters upon the bars 15, and passes thence to the screen 16, through which the water passes to the outlet or exit 6 at the bottom of the casing.

In front of the lower end of the strainer 95 15 the side wall of the casing is provided with a lateral outlet-opening, 17, a similar opening being provided in the side wall of

the casing at the lower end of the other strainer, 16. The side edges of these lateral outlet-openings 17 are provided with vertical grooves or guideways, and in the latter are arranged the vertical edges of sliding gates 18, which may be thrown down to the foot of either the parallel bars or to the foot of the foraminous screen to intercept the descending current of water flowing over either the parallel bars or the foraminous or perforated screen, and thus force the water to pass through the strainers. By raising either of these gates the accumulation of matter floating in the current may be discharged, and thus the casing may be kept clean and the water passing through the casing may be rendered suitable for drinking or other similar purposes.

In Figs. 4 and 5 the parts numbered as in preceding figure have an identical use and the same general mechanical structure. In these figures three strainers are used, all slanted in the same direction, and the openings 17 and the gates 18 are all on the same edge, and the other edge is made watertight all the way down, and the bars 15 and the screen 16 and the perforated tin 23 are swayed downward near the middle to serve as a check to the outward or lateral current of water. In Fig. 5 a turn-back or duct, 22, is used to carry the water (running down the screens near the gates 18) back and drop it on the highest part of the next strainer or screen.

35. What we claim is—

1. The combination, with a casing having an inlet and two outlets, and provided at its top with a longitudinal slot arranged in a vertical plane, of a tilting chute pivoted at or near its center in the casing, and a swinging and lengthwise-movable lever extending through and resting on the lower edge of the slot, and having its inner extremity pivoted to one end of the tilting chute, said lever provided at its outer end with a weight, serving to force the lever down upon the lower edge of said slot to hold the chute in its adjusted position, substantially as described.

50. 2. The combination, with a casing having a slot in its top, a top inlet, a lateral side outlet, and a bottom outlet, of an inclined duct rising from the side outlet and extending inward and upward, a tilting chute pivoted at or near its center above the upper end of the inclined duct, and a swinging and lengthwise-movable lever extending through and resting on the lower edge of the slot, and having its inner extremity pivoted to one end of the tilting chute and its outer end carrying a weight for forcing the lever into contact with the lower edge of the slot, substantially as and for the purposes described.

65. 3. The combination, with a casing having an inlet, a lateral side outlet, and a bottom

outlet, of inclined strainers located between the lateral side outlet and the bottom outlet, an inclined duct rising from the side outlet and extending upward and inward above the strainers, a tilting chute pivoted at or near its center above the strainers and duct, and a lever for tilting the chute, substantially as described.

4. The combination, with a casing, 1, having an inlet, 5, a lateral side outlet, 14, a bottom outlet, 6, and lateral side orifices, 17, of oppositely-inclined strainers 15 and 16, rising from the lateral side orifices, an adjustable gate, 18, located in each of said orifices at the lower end of the strainer rising therefrom, an inclined duct, 19, rising from the lateral side outlet and extending upward and inward above the strainers, a tilting chute, 8, pivoted above the upper end of the chute, and a lever for tilting the chute, substantially as described.

5. The combination, with the casing 1, having a top inlet, 5, a bottom outlet, 6, and a series of lateral outlet-openings, 17, provided at their sides with vertical guideways, a series of inclined strainers arranged in the casing and having their lower edges extending down to the lower edges of said lateral outlets, and a series of vertically-sliding gates, 18, having their vertical edges arranged in said guideways, said gates when raised permitting the water passing down the strainers to flow laterally to the outside of the casing, and when lowered to the edges of the strainers intercepting the downflow and forcing it back upon the strainers, substantially as described.

6. In a water filter and cut-off, the combination, with a casing having an upper and a lower outlet, of an inclined strainer composed of parallel straight bars, and an oppositely-inclined straight strainer composed of a foraminous plate, substantially as described.

7. In a water filter and cut-off, the combination, with a casing having an upper inlet and a lower outlet, and provided with a series of inclined bars and with an oppositely-inclined foraminous plate, of vertically-movable gates mounted in the edges of the casing at the foot of the inclined bars and at the foot of the foraminous plate, substantially as described.

8. The combination, with the casing 1, having an inlet, 5, and outlet 6, and provided with the inclined chute 19, of the pivoted chute 8, gravity-lever 10, the inclined bars 15, and the oppositely-inclined screen 16, substantially as described.

In testimony whereof we affix our signatures in presence of two witnesses.
